GOLF CLUB BRUSH

George E. Lion, 701 Manning Ave., Port Vue, Pa.

Filed Dec. 23, 1964, Ser. No. 83,143

Term of patent 14 years

(Cl. D9—2)

Fig. 1.

Fig. 2.

Fig. 3.

I claim:

The ornamental design for a golf club brush, as shown and described.
